CONTINUOUS FORM ENVELOPE

Donald J. Steidinger, Clarendon Hills, Ill., assignor to
Uarco Incorporated, a corporation of Illinois
Filed Mar. 8, 1961, Ser. No. 94,326
19 Claims. (Cl. 93—63)

This invention relates to a method of forming a continuous form assembly of detachable envelopes and more particularly to a method which produces such a product from a single web of envelope material or paper.

Continuous form assemblies of detachable envelopes have been produced in the past, for example, see Patent No. 2,824,685 and my Patent No. 2,895,534. Both of these patents show assemblies of series-connected envelopes. However, it is apparent from their disclosures that these envelopes are not constructed from a single web material but are constructed from two webs of material. Obviously, it is desirable to be able to produce envelopes of this form from a single web material.

It is therefore an object of this invention to provide a method for forming a continuous form assembly of detachable envelopes from a single web of paper.

It is another object of this invention to provide a method of forming a continuous form assembly of detachable envelopes from a single web of paper comprising the steps of die-cutting a web of envelope material at longitudinally spaced points to form elongated, longitudinally spaced, transversely extending flaps which are adapted to be folded laterally across the web to define the back of an envelope having a pocket therein, applying adhesive material along the envelope bottom defining edge of the flaps and along the longitudinal edge of the flaps, folding the flaps across the web and joining them thereto in the areas bearing said adhesive and providing means for separating between adjacent individual envelopes to enable the envelopes to be readily detached from each other.

It is still another object of this invention to provide an envelope wherein the elongated, longitudinally spaced, transversely extending flaps are located in pairs on opposite sides of the web.

It is yet a further object of this invention to provide such an envelope wherein each of the flaps is scored at the area of connection between the flaps and the web to provide a fold line.

It is still another object of this invention to provide such a method wherein adhesive is applied along the margin of the web adjacent the connecting area between the flaps and the web and the continuous form is provided with regularly spaced apertures or line holes in the marginal portion of the web to facilitate the feed of the assembly through a business machine.

It is yet another object of this invention to provide such a method wherein lines of weakening are provided adjacent to but spaced inwardly from the spaced apertures or line holes for removal of the margins bearing the same after use.

It is yet a further object of this invention to provide such a method wherein the web is provided with a plurality of pairs of openings each located adjacent the margin of the web at a point substantially coinciding with the longitudinal spacing between said flaps and defining therebetween an envelope top flap.

It is still another object of this invention to provide such a method wherein the top flap has been provided with a strip of adhesive and a folding crease between the top flap and the envelope face.

Other objects and advantages of the invention will become apparent from the following description taken together with the following drawings.

Of the drawings:

FIGURE 1 is a flow diagram showing one sequence

2

of the steps of the method of this invention with numbered boxes indicating the operation performed at each step and in each piece of equipment;

FIGURES 2 through 8 are partial top plan views in varying sizes related by number to the boxes I—VII in FIGURE 1 and each showing the result of the operation performed on the web at that step of the process;

FIGURE 9 is a perspective view in reduced size of a partially folded group of continuous form envelopes;

FIGURE 10 is a top plan view of an envelope of this invention;

FIGURE 11 is a sectional view taken along the line 11—11 of FIGURE 10;

FIGURE 12 is a sectional view taken along the line 12—12 of FIGURE 10; and

FIGURES 13 and 14 are perspective views from the back and front of a separated envelope of this invention.

Referring now to the drawings, FIGURE 1 as previously pointed out, is a diagrammatic layout of the steps of this invention. The order shown in FIGURE 1 is not necessarily the order in which the steps must be accomplished, as will be apparent through the description of the method of this invention. Each of the numbered boxes shown in FIGURE 1 identifies a step being performed and for clarity of description, the steps will be described in this order and related to FIGURES 2 through 8 which show the results of the steps.

It must be pointed out first of all, that the continuous form envelopes of this invention are produced by a method which allows the use of a single web of paper. As can be seen clearly in FIGURE 1, a single roll 10 of paper or other envelope material is mounted at a position corresponding to the beginning of an assembly line and feeds a single web 11 of paper into the first step. This same web 11 passes through the whole process.

Step I shown in the process of FIGURE 1 is that of printing on the envelope. As can be seen in FIGURE 2, the web 11 after passing through the printer 12 has imposed on what will be the face of the envelope the name 13 of the company or user. Obviously, of course, this printed step could be accomplished at almost any time during the process of this invention.

At Step II, the top flap gum or adhesive 14 of the envelope is applied and dried by means of an adhesive applicator 15. The adhesive used is one which on moistening will seal the envelope.

The web of paper 11 next passes to Step III which involves the punching of side panels or flaps 16 and 17. The score line 18 is also provided on which the flaps 16 and 17 can be folded. This operation is performed in a punch mechanism 19 which imposes a plurality of punches or cuts on the continuous web 11. Thus punches are made along the lines 20a, 20b and 20c to define one side of two side flaps 16, and along the lines 21a, 21b and 21c to define one side of two side flaps 17. At the same time, the web is scored at 18 which is substantially the area of connection between the side flaps 16 and 17, and the main web to provide a fold on which the flaps 16 and 17 may be laterally folded to define the envelope back. It will be noted that flap 16 is substantially shorter than flap 17. This provides an offset connection at 22 between the flaps as the envelope is formed (see FIGURE 14). The purpose of the offset flaps is to make possible a "penny saver" end flap which can be opened for postal inspection. This feature would allow mail to be sent with one cent less postage. In order to provide the "penny saver" end flap, the envelope is constructed the same as shown in the drawings and as described with the exception of the glue pattern on the short flap at 16a and 16b. One or two small spots of glue (not shown) are substituted for the lines of glue 16a and 16b so that a postal inspector can pull out the short flap 16, inspect

the contents, restuff them and push in the flap. The line of glue 23 remains the same to form a strong seal on that side.

The web next moves to Step IV during which glue is applied to the side panels or flaps 16 and 17 by a glue applicator 24. In FIGURE 5, it can be seen that glue is applied along the bottom 16a and 17a of the flaps 16 and 17. This is the area which will define the bottom of the envelope. Glue is also applied along the longitudinal side edge 16b of the flap 16. Additionally, strips 23 of glue are applied along the web at a point adjacent the connection between the flaps 16 and 17, and the web 11. The strips 23 of glue are continuously extending even along the portion of the web between the flaps 16 and 17. This glue is normally a conventional liquid glue which dries rather quickly on standing and is applied in a conventional glue applicator 24.

After leaving the glue applicator 24 in Step IV, the web 11 passes into side panel folding and drying, Step V, which involves the use of a piece of equipment 25 designed for this purpose. During this step, as can be seen in FIGURE 6, the side panels 16 and 17 are folded over and joined together by the adhesive strips 16b and are adhered along the bottom of the envelope by the strips 16a and 17b. The adhesive 23 is also joined to the end portions 11a and 11b of the web 11 to facilitate the later addition of line holes. The adhesive is dried in the same step so that a sturdy construction results.

The web 11 next passes into Step VI wherein a device 26 punches flap holes 27 which define a top flap 30 and provides scores 28 between adjacent envelopes. The scores 28 are lines of weakening which allow the envelopes to be separated after passing through a business machine. In this same step a crease 29 is provided adjacent the top flap 20 on which the flap is folded after the contents of the envelope are placed therein. Line holes 32 which are used to guide the forms through a business machine are also added during this step.

In Step VII which is performed by a scoring mechanism and side trimming machine 31, the edges 33 are trimmed to cut away unnecessary envelope forming material, and the lines of weakening 35 are added. These facilitate removal of the margins bearing the line holes 32 after the envelopes have been used in a business machine.

After leaving operation VII, the now formed strip of envelopes passes into a folder 34 which is Step VIII wherein they are folded into the pack shown in FIGURE 9, for packing and shipping.

As can be seen in FIGURES 10 through 14, the envelope 40 after separation from the pack along the line of weakening 28 and after slitting away the scored margin 35 in a conventional slitter (not shown), may be used for all convenient business purposes. It is of conventional size and shape, and because of its single web construction, looks very much like singly made envelopes.

The foregoing detailed description has been given for clearness of understanding only, and no unnecessary limitations should be understood therefrom for some modifications will be obvious to those skilled in the art.

I claim:

1. A method of forming a continuous form assembly of detachable envelopes from a single web of paper, comprising the steps of: die-cutting a web of envelope material at longitudinally spaced points along both edges of said web to form elongated, longitudinally spaced, transversely extending flaps which are adapted to be folded laterally across said web to define the back of an envelope having a pocket therein; applying adhesive material along the envelope bottom defining edge of said flaps and along the longitudinal edge of at least some of said flaps; folding said flaps across said web and joining them thereto and together in the areas bearing said ad-

hesive; and providing means for separating between adjacent individual envelopes to enable said envelopes to be readily detached from each other after use in continuous form machinery and the like.

5 2. A method of forming a continuous form assembly of detachable envelopes from a single web of paper, comprising the steps of: die-cutting a web of envelope material at longitudinally spaced points along both edges of said web to form oppositely located pairs of elongated, longitudinally spaced, transversely extending flaps, each 10 pair of which is adapted to be folded laterally across said web to define the back of an envelope having a pocket therein; applying adhesive material along the envelope bottom defining edge of said flaps and along the longitudinal edge of one of the flaps in each pair; folding said flaps across said web and joining them thereto and together in the areas bearing said adhesive; and providing means for separating between adjacent individual envelopes to enable said envelopes to be readily detached from each other after use in continuous form machinery and the like.

15 3. The method of claim 2 where one member of said pair of flaps is longer than the other member.

20 4. A method of forming a continuous form assembly of detachable envelopes from a single web of paper, comprising the steps of: die-cutting a web of envelope material at longitudinally spaced points along both edges of said web to form elongated, longitudinally spaced, transversely extending flaps which are adapted to be 25 folded laterally across said web to define the back of an envelope having a pocket therein; scoring each of said flaps at the area of connection between said flaps and said web to provide a fold line; applying adhesive material along the envelope bottom defining edge of 30 said flaps and along the longitudinal edge of at least some of said flaps; folding said flaps across said web on said fold line and joining them to said web and together in the areas bearing said adhesive; and providing means for separating between adjacent individual envelopes to enable said envelopes to be readily detached from each other after use in continuous form machinery and the like.

35 5. A method of forming a continuous form assembly of detachable envelopes from a single web of paper, comprising the steps of: die-cutting a web of envelope material at longitudinally spaced points along both edges of said web to form oppositely located pairs of elongated, longitudinally spaced, transversely extending flaps, each 40 pair of which is adapted to be folded laterally across said web to define the back of an envelope having a pocket therein; scoring each of said flaps at the area of connection between said flaps and said web to provide a fold line; applying adhesive material along the envelope bottom defining edge of said flap and along the longitudinal edge of one of the flaps in each pair; folding said flaps across said web on said fold line and joining them to said web and together in the areas bearing said adhesive; and providing means for separating between adjacent individual envelopes to enable said envelopes to be readily detached from each other after use in continuous form machinery and the like.

45 6. A method of forming a continuous form assembly of detachable envelopes from a single web of paper, comprising the steps of: die-cutting a web of envelope material at longitudinally spaced points along both edges of said web to form elongated, longitudinally spaced, transversely extending flaps which are adapted to be 50 folded laterally across said web to define the back of an envelope having a pocket therein; applying adhesive material along the envelope bottom defining edge of said flaps, along the longitudinal edge of said flaps and along the margins of said web adjacent the connecting area between said flaps and said web; folding said flaps across said web and joining them thereto and together 55 in the areas bearing said adhesive; providing means for

separating between adjacent individual envelopes to enable said envelopes to be readily detached from each other after use in continuous form machinery and the like; and providing regularly spaced apertures in the marginal portion of said web to facilitate the feed of the assembly through a business machine.

7. A method of forming a continuous form assembly of detachable envelopes from a single web of paper, comprising the steps of: die-cutting a web of envelope material at longitudinally spaced points along both edges of said web to form oppositely located pairs of elongated, longitudinally spaced, transversely extending flaps, each pair of which is adapted to be folded laterally across said web to define the back of an envelope having a pocket therebetween; applying adhesive material along the envelope bottom defining edge of said flaps, along the longitudinal edge of said flaps and along the margins of said web adjacent the connecting area between said flaps and said web; folding said flaps across said web and joining them thereto and together in the areas bearing said adhesive; providing means for separating between adjacent individual envelopes to enable said envelopes to be readily detached from each other after use in continuous form machinery and the like; and providing regularly spaced apertures in the marginal portion of said web to facilitate the feed of the assembly through a business machine.

8. A method of forming a continuous form assembly of detachable envelopes from a single web of paper, comprising the steps of: die-cutting a web of envelope material at longitudinally spaced points along both edges of said web to form elongated, longitudinally spaced, transversely extending flaps which are adapted to be folded laterally across said web to define the back of an envelope having a pocket therein; scoring each of said flaps at the area of connection between said flaps and said web to provide a fold line; applying adhesive material along the envelope bottom defining edge of said flaps, along the longitudinal edge of said flaps and along the margins of said web adjacent the connecting area between said flaps and said web; folding said flaps across said web on said fold line and joining them to said web and together in the areas bearing said adhesive; providing means for separating between adjacent individual envelopes to enable said envelopes to be readily detached from each other after use in continuous form machinery and the like; and providing regularly spaced apertures in the marginal portion of said web to facilitate the feed of the assembly through a business machine.

9. A method of forming a continuous form assembly of detachable envelopes from a single web of paper, comprising the steps of: die-cutting a web of envelope material at longitudinally spaced points along both edges of said web to form oppositely located pairs of elongated, longitudinally spaced, transversely extending flaps, each pair of which is adapted to be folded laterally across said web to define the back of an envelope having a pocket therein; scoring each of said flaps at the area of connection between said flaps and said web to provide a fold line; applying adhesive material along the envelope bottom defining edge of said flaps, along the longitudinal edge of said flaps and along the margins of said web adjacent the connecting area between said flaps and said web; folding said flaps across said web on said fold line and joining them to said web and together in the areas bearing said adhesive; providing means for separating between adjacent individual envelopes to enable said envelopes to be readily detached from each other after use in continuous form machinery and the like; and providing regularly spaced apertures in the marginal portion of said web to facilitate the feed of the assembly through a business machine.

10. A method of forming a continuous form assembly of detachable envelopes from a single web of paper, com-

prising the steps of: die-cutting a web of envelope material at longitudinally spaced points along both edges of said web to form oppositely located pairs of elongated, longitudinally spaced, transversely extending flaps, each pair of which is adapted to be folded laterally across said web to define the back of an envelope having a pocket therein; scoring each of said flaps at the area of connection between said flaps and said web to provide a fold line; applying adhesive material along the envelope bottom defining edge of said flaps, along the longitudinal edge of said flaps and along the margins of said web adjacent the connecting area between said flaps and said web; folding said flaps across said web on said fold line and joining them to said web and together in the areas bearing said adhesive; providing means for separating between adjacent individual envelopes to enable said envelopes to be readily detached from each other after use in continuous form machinery and the like; providing regularly spaced apertures in the marginal portion of said web to facilitate the feed of the assembly through a business machine; and providing lines of weakening adjacent but spaced inwardly from said spaced apertures for removal of the margins bearing the same after use.

11. A method of forming a continuous form assembly of detachable envelopes from a single web of paper, comprising the steps of: die-cutting a web of envelope material at longitudinally spaced points to form elongated, longitudinally spaced, transversely extending flaps which are adapted to be folded laterally across said web to define the back of an envelope having a pocket therein; applying adhesive material along the envelope bottom defining edge of said flaps and along the longitudinal edge of said flaps; folding said flaps across said web and joining them thereto in the areas bearing said adhesive; providing means for separating between adjacent individual envelopes to enable said envelopes to be readily detached from each other after use in continuous form machinery and the like; and providing a plurality of pairs of openings in said web, each opening of said pair being located adjacent the margin of said web at a point substantially coinciding with the longitudinal spacing between said flaps and defining therebetween an envelope top flap.

12. A method of forming a continuous form assembly of detachable envelopes from a single web of paper, comprising the steps of: die-cutting a web of envelope material at longitudinally spaced points along both edges of said web to form elongated, longitudinally spaced, transversely extending flaps which are adapted to be folded laterally across said web to define the back of an envelope having a pocket therein; applying adhesive material along the envelope bottom defining edge of said flaps and along the longitudinal edge of at least some of said flaps; folding said flaps across said web and joining them thereto and together in the areas bearing said adhesive; providing means for separating between adjacent individual envelopes to enable said envelopes to be readily detached from each other after use in continuous form machinery and the like; and providing a plurality of pairs of openings in said web, each opening of said pair being located adjacent the margin thereof at a point substantially coinciding with the longitudinal spacing between said flaps and defining therebetween an envelope top flap.

13. A method of forming a continuous form assembly of detachable envelopes from a single web of paper, comprising the steps of: die-cutting a web of envelope material at longitudinally spaced points along both edges of said web to form oppositely located pairs of elongated, longitudinally spaced, transversely extending flaps, each pair of which is adapted to be folded laterally across said web to define the back of an envelope having a pocket therein; applying adhesive material along the envelope bottom defining edge of said flaps and along the longitudinal edge of one of the flaps in each pair; folding said flaps across said web and joining them thereto and to-

gether in the areas bearing said adhesive; providing means for separating between adjacent individual envelopes to enable said envelopes to be readily detached from each other after use in continuous form machinery and the like; and providing a plurality of pairs of openings in said web, each opening in said pair being located adjacent the margin of said web at a point substantially coinciding with the longitudinal spacing between said flaps and defining therebetween an envelope top flap.

14. A method of forming a continuous form assembly of detachable envelopes from a single web of paper, comprising the steps of: die-cutting a web of envelope material at longitudinally spaced points to form elongated, longitudinally spaced, transversely extending flaps which are adapted to be folded laterally across said web to define the back of an envelope having a pocket therein; scoring each of said flaps at the area of connection between said flaps and said web to provide a fold line; applying adhesive material along the envelope bottom defining edge of said flaps, along the longitudinal edge of said flaps and along the margin of said web adjacent the connecting area between said flaps and said web; folding said flaps across said web on said fold lines and joining them to said web in the areas bearing said adhesive; providing means for separating between adjacent individual envelopes to enable said envelopes to be readily detached from each other after use in continuous form machinery and the like; providing regularly spaced apertures in the marginal portion of said web to facilitate the feed of the assembly through a business machine; and providing a plurality of pairs of openings in said web, each opening of a pair being located adjacent the margin thereof at a point substantially coinciding with the longitudinal spacing between said flaps and defining therebetween an envelope top flap.

15. A method of forming a continuous form assembly of detachable envelopes from a single web of paper, comprising the steps of: die-cutting a web of envelope material at longitudinally spaced points along both edges of said web to form elongated, longitudinally spaced, transversely extending flaps which are adapted to be folded laterally across said web to define the back of an envelope having a pocket therein; scoring each of said flaps at the area of connection between said flaps and said web to provide a fold line; applying adhesive material along the envelope bottom defining edge of said flaps, along the longitudinal edge of some of said flaps and along the margins of said web adjacent the connecting area between said flaps and said web; folding said flaps across said web on said fold line and joining them to said web and together in the areas bearing said adhesive; providing means for separating between adjacent individual envelopes to enable said envelopes to be readily detached from each other after use in continuous form machinery and the like; providing regularly spaced apertures in the marginal portion of said web to facilitate the feed of the assembly through a business machine; and providing a plurality of pairs of openings in said web, each opening of a pair being located adjacent the margin thereof at a point substantially coinciding with the longitudinal spacing between said flaps and defining therebetween an envelope top flap.

16. A method of forming a continuous form assembly of detachable envelopes from a single web of paper, comprising the steps of: die-cutting a web of envelope material at longitudinally spaced points along both edges of said web to form oppositely located pairs of elongated, longitudinally spaced, transversely extending flaps, each pair of which is adapted to be folded laterally across said web to define the back of an envelope having a pocket therein; scoring each of said flaps at the area of connection between said flaps and said web to provide a fold line; applying adhesive material along the envelope bottom defining edge of said flaps, along the longitudinal edge of one of said flaps in each pair and along the margins of said web adjacent the connecting area between said flaps and said web; folding said flaps across said web

5 on said fold line and joining them to said web and together in the areas bearing said adhesive; providing means for separating between adjacent individual envelopes to enable said envelopes to be readily detached from each other after use in continuous form machinery and the like; providing regularly spaced apertures in the marginal portion of said web to facilitate the feed of the assembly through a business machine; and providing a plurality of pairs of openings in said web, each opening of a pair located adjacent the margin thereof at a point substantially coinciding with the longitudinal spacing between said flaps and defining therebetween an envelope top flap.

10 17. A method of forming a continuous form assembly of detachable envelopes from a single web of paper, comprising the steps of: die-cutting a web of envelope material at longitudinally spaced points to form elongated, longitudinally spaced, transversely extending flaps which are adapted to be folded laterally across said web to define the back of an envelope having a pocket therein; scoring each of said flaps at the area of connection between said flaps and said web to provide a fold line; applying adhesive material along the envelope bottom defining edge of said flaps, along the longitudinal edge of said flaps and along the margin of said web adjacent the connecting area between said flaps and said web; folding said flaps across said web on said fold line and joining them to said web in the areas bearing said adhesive; providing means for separating between adjacent individual envelopes to enable said envelopes to be readily detached from each other after use in continuous form machinery and the like; providing regularly spaced apertures in the marginal portion of said web to facilitate the feed of the assembly through a business machine; providing a plurality of pairs of openings in said web, each opening being located adjacent the margin of said web at a point substantially coinciding with the longitudinal spacing between said flaps and defining therebetween an envelope top flap; and providing a strip of adhesive on said top flap and a folding crease between said top flap and said envelope face.

15 18. A method of forming a continuous form assembly of detachable envelopes from a single web of paper, comprising the steps of: die-cutting a web of envelope material at longitudinally spaced points along both edges of said web to form elongated, longitudinally spaced, transversely extending flaps which are adapted to be folded laterally across said web to define the back of an envelope having a pocket therein; scoring each of said flaps at the area of connection between said flaps and said web to provide a fold line; applying adhesive material along the envelope bottom defining edge of said flaps, along the longitudinal edge of said flaps and along the margins of said web adjacent the connecting area between said flaps and said web; folding said flaps across said web on said fold line and joining them to said web and together in the areas bearing said adhesive; providing means for separating between adjacent individual envelopes to enable said envelopes to be readily detached from each other after use in continuous form machinery and the like; providing regularly spaced apertures in the marginal portion of said web to facilitate the feed of the assembly through a business machine; providing a plurality of pairs of openings in said web, each opening of a pair being located adjacent the margin of said web at a point substantially coinciding with the longitudinal spacing between said flaps and defining therebetween an envelope top flap; and providing a strip of adhesive on said top flap and a folding crease between said top flap and said envelope face.

20 19. A method of forming a continuous form assembly of detachable envelopes from a single web of paper, comprising the steps of: die-cutting a web of envelope material at longitudinally spaced points along both edges of said web to form oppositely located pairs of elongated, longitudinally spaced, transversely extending flaps, each pair of which is adapted to be folded laterally across said

web to define the back of an envelope having a pocket therein; scoring each of said flaps at the area of connection between said flaps and said web to provide a fold line; applying adhesive material along the envelope bottom defining edge of said flaps, along the longitudinal edge of said flaps and along the margins of said web adjacent the connecting area between said flaps and said web; folding said flaps across said web on said fold line and joining them to said web and together in the areas bearing said adhesive; providing means for separating between adjacent individual envelopes to enable said envelopes to be readily detached from each other after use in continuous form machinery and the like; providing regularly spaced apertures in the marginal portion of said web to facilitate the feed of the assembly through a business machine; providing a plurality of pairs of openings in said web, each opening of a pair being located adjacent the margin thereof at a point substantially coinciding with the longi-

tudinal spacing between said flaps and defining therebetween an envelope top flap; and providing a strip of adhesive on said top flap and a folding crease between said top flap and said envelope face.
